UNITED STATES PATENT OFFICE.

ROBERT HEAD, OF NEW YORK, N. Y., ASSIGNOR TO THE AEOLIAN COMPANY, A CORPORATION OF CONNECTICUT.

SOUND-BOX.

1,334,094.

Specification of Letters Patent. Patented Mar. 16, 1920.

Application filed August 9, 1917, Serial No. 185,316. Renewed October 9, 1918. Serial No. 257,530.

To all whom it may concern:

Be it known that I, ROBERT HEAD, a citizen of the United States, residing at New York, in the county of New York and State of New York, have invented new and useful Improvements in Sound-Boxes, of which the following is a specification.

This invention relates to sound-boxes for talking machines, and in particular to those 10 of the so-called convertible or universal type, which may be used to play records of both the vertical- and the lateral-cut forms.

Under ordinary conditions, it is customary to employ a jewel-tipped stylus with 15 records having vertical-cut or hill-and-dale sound grooves, and a sharp-pointed stylus or needle of steel or other suitable non-crystalline material with records having lateral-cut or zig-zag grooves. In certain known 20 forms of sound-boxes, two separate stylus-holders are provided, one for each character of stylus, and in certain other forms, a shiftable holder is utilized which is selectively movable from one position to another, ac- 25 cording to the type of record to be played; but in both cases at least two separate clamp- ing screws or their equivalents are neces- sary, for in the first case each holder has its 30 own clamping device, and in the second case a screw or other clamp is required to secure the holder in adjusted position.

According to the present invention, how- 35 ever, the arrangement is greatly simplified, and its cost of construction correspondingly decreased, by providing a novel and im- proved clamp for firmly and securely hold- 40 ing the movable holder in either of its two playing positions and also by providing a single clamp which serves both to retain the 45 movable holder in adjusted position, and to maintain the stylus in place. Furthermore, the holder is formed with two separate stylus-sockets, one for use when one type of record is being played, and the other for use 50 when playing a record of the other type; and both of these sockets are controlled by the aforesaid clamp, which will hold the stylus in position as well in one socket as in the other.

55 Other features and advantages will present themselves as the description proceeds.

An embodiment of the invention is illus- trated in the accompanying drawing, where- in:

Figure 1 is a face view of a sound-box 55 equipped with the invention, the holder being positioned to play a lateral-cut record.

Fig. 2 is an edge view thereof.

Fig. 3 is a fragmental view similar to Fig. 2, but showing the holder adjusted to 60 play a vertical-cut record.

Fig. 4 is an enlarged, part-sectional de- 65 tail view, showing the holder in Fig. 1 position.

Fig. 5 is a part-sectional view of the 65 holder, showing the two stylus sockets, but with the clamp omitted.

Fig. 6 is a detail view, showing the holder 70 in Fig. 4 position, but in side elevation instead of section.

Referring more particularly to said drawing, 1 designates the body of the sound-box, 2 the diaphragm thereof, 3 the stylus bar, and 4 the spaced supporting parts or lugs 75 for the bearing-screws 5, between which lat- ter the stylus bar is mounted to oscillate. All of the above parts function in the usual man- ner, and, with the exception of the stylus bar, are, or may be, of the usual or any de- 80 sired construction.

The stylus bar, according to this invention, is made in two structurally-separate parts 3' and 3'', the upper part or member 3' being fastened at its upper end to the dia- phragm in the usual way, while the lower part 3'' functions as the stylus holder and is 85 adjustable relatively to the said upper part. The lower portion 6 of the member 3' is 90 enlarged or headed, and is provided with oppositely-projecting pins or trunnions 7, 95 the latter being disposed between the lugs 4 and engaged at their terminals by the screws 5, so that they unite in forming the pivotal axis about which the stylus bar as a whole rocks. The lower member 3'' of the 95 bar presents the most important features of the invention; and, according to the embodi- ment illustrated, which may be considered for all practical purposes as preferred, it con- 100 sists of a cruciform body, the upper arm of which has a substantially greater length than the other arms but is cut away at its free end, thus producing a shoulder 8 and a seat 9, at the side thereof. This seat receives the head 6, which is rounded, as shown, 105 while the shoulder 8 fits against one face of said head and is formed with an opening for the passage of the adjacent trunnion 7.

therethrough, the trunnion serving as the axis about which the body 3² rocks during its movement from one position to the other.

The two branches of the cross-shaped body 3² are provided with inwardly-extending passages or sockets 10 and 10', which intersect each other at the center of said body, as represented in dotted lines at 10² in Fig. 5. One of these sockets is designed 10 to receive the stylus when the holder is in position for playing lateral-cut records; and in such case that particular socket, which is indicated at 10 in Figs. 4 and 5, will substantially align with the upper member of 15 the stylus bar. The other socket 10' receives the stylus when a vertical-cut record is being played, at which time the socket is arranged in spaced, parallel relation to the aforesaid upper member 3', instead of in 20 longitudinal or axial alinement therewith, the parts being then in Fig. 3 position, and the holder having been turned through an angle of 90°. It will be apparent, therefore, that inasmuch as the two sockets 10 25 and 10' cross each other, a single clamping screw 11 may be employed to control both sockets—that is to say, to hold the needle or stylus in place in either playing position of the holder—the inner end of the screw 30 extending loosely through a hole in the holder located at the point of intersection 10² of the sockets and impinging against the stylus.

This screw 11 is not only used to retain a 35 stylus in place in one or the other of the sockets 10 and 10', but it also serves, in the preferred construction shown, to secure the holder itself in adjusted position; for it must be borne in mind that the holder has 40 an angular movement of 90° in changing from either position to the other. Accordingly, there is provided a supplemental clamping member 12 preferably in the form of a small plate, which is arranged against 45 the front face of the holder, its upper portion being disposed against the opposite face of the head 6 from that with which the shoulder 8 contacts, and having an opening through which the front trunnion 7 loosely 50 passes, so that in this way a balanced pivotal mounting is provided for the holder, and the plate itself is pivotally supported. The central portion of the plate is formed with an opening through which a small, headed 55 screw 13 is loosely inserted, the screw extending into a threaded opening in the elongated arm of the holder and serving to connect the plate and holder together. At its lower portion, the said plate is provided 60 with a threaded opening; and through this threaded opening the clamping screw 11 is passed, so that when said clamping screw is turned in either direction, the plate will be caused to rock slightly about the coupling screw 13 as a fulcrum, with the result that

its upper end is forced tightly against, or withdrawn from the adjacent face of the head 6, according as the clamping screw is turned in a direction to advance or to retract it through the opening in the holder, 70 thus alternatively locking or releasing the holder as will be understood. Consequently, a stylus may be inserted in the proper socket in the holder, and the latter then turned to the required position and made fast by 75 means of the clamping screw, which, at the same time, also secures the stylus in its socket.

I claim as my invention—

1. In a sound-box, the combination, with 80 a stylus bar having a relatively-movable stylus-holding portion; of a single clamp for retaining said portion in adjusted position and for securing a stylus in place therein.

2. In a sound-box, the combination, with 85 a jointed stylus bar comprising a socketed stylus-holding member movable into position to alternatively play vertical- and lateral-cut records; of a single fastening means for retaining said holder in either 90 position and for securing a stylus in its socket.

3. In a sound-box, the combination, with 95 a jointed stylus bar comprising a socketed stylus-holding member movable into position to alternatively play vertical- and lateral-cut records; of a single clamping screw adjustable to fasten said holder in either position and simultaneously secure 100 a stylus in its socket.

4. In a sound-box, the combination, with 105 a pair of spaced, supporting parts; of a stylus bar comprising an upper member pivoted between said parts, and a lower stylus-holding member pivoted to said upper member for movement relatively to the same into position to alternatively play vertical- and lateral-cut records; and a single clamping device for fastening said stylus-holding member in either of its two positions and 110 for simultaneously securing a stylus in place therein.

5. In a sound-box, the combination, with 115 a pair of spaced, supporting parts; of a stylus bar comprising an upper member pivoted between said parts, and a lower stylus-holding member pivoted to said upper member for movement relatively to the same into position to alternatively play vertical- and lateral-cut records; a plate for 120 retaining said stylus-holding member in either of its two positions; and a clamping screw for operating said plate and simultaneously fastening a stylus in place in said holding member.

6. In a sound-box, the combination, with 125 a pair of spaced, supporting parts; of a stylus bar comprising an upper member having a pair of oppositely-projecting trunnions disposed between and pivotally sup- 130

ported by said spaced parts, and a lower stylus-holding member pivotally mounted on one of said trunnions for movement into position to alternatively play vertical- and lateral-cut records; a plate pivotally mounted on the other trunnion and fulcrumed intermediate its ends on said stylus holder; and a single clamping member for rocking said plate about its fulcrum into binding engagement with the trunnioned member and for simultaneously securing a stylus in place in said holder.

7. In a sound-box, the combination, with a pair of spaced, supporting parts; of a stylus bar comprising an upper member having a pair of oppositely-projecting trunnions disposed between and pivotally supported by said spaced parts, and a lower stylus-holder member pivotally mounted on one of said trunnions for movement into position to alternatively play vertical- and lateral-cut records; a plate suspended at its upper end from the other trunnion and fulcrumed intermediate its ends on said stylus holder, the lower end of said plate having a threaded opening which overlies an aperture in the socket holder; and a clamping screw having its stem engaged with the threads of said opening and passing loosely through said aperture, thereby to rock said plate about its fulcrum into binding engagement with the trunnioned member and to simultaneously impinge against a stylus in said holder.

8. In a sound-box, a stylus bar comprising an upper member, and a lower member movably related thereto and having two stylus-holding sockets; one for playing vertical-cut records and the other for lateral-cut records, said holder being shiftable to bring either socket into active position; and a single clamp for controlling the retention of a stylus in either socket.

9. In a sound-box, a stylus bar comprising an upper member, and a lower member movably related thereto and having two stylus-holding sockets, one for playing vertical-cut records and the other for lateral-cut records, said holder being shiftable to bring either socket into active position; and a single device for clamping said holder in either position and for retaining a stylus in the active socket.

10. In a sound-box, a stylus bar comprising an upper member, and a lower member movably related thereto and having two stylus-holding sockets, one for playing vertical-cut records and the other for lateral-cut records, said holder being shiftable to bring either socket into active position; and a single clamping screw for retaining said holder in either position and for engaging a stylus in the active socket.

11. In a sound-box, a stylus bar having a cruciform stylus holder, the branches of

which are formed with two intersecting sockets, one for playing vertical-cut records and the other for lateral-cut records, said holder having an opening at the point of intersection of said sockets and being movable relatively to the stylus bar to bring either socket into playing position; and a clamping member having a portion thereof arranged in said opening, so as to engage a stylus in either socket.

70

75

12. In a sound-box, a stylus bar having a cruciform stylus holder, each branch of which is formed with a socket, one socket for playing vertical-cut records and the other for lateral-cut records, said holder being adjustable relatively to the bar to bring either socket into playing position; and a single clamping device common to both sockets for retaining a stylus in the active socket and for simultaneously retaining the holder in adjusted position.

80

85

13. In a sound-box, the combination of a stylus-bar having a stylus-socket, a clamping-plate supported on the stylus-bar, and a screw which operates said clamping-plate at the same time that it secures the stylus in the stylus-bar socket.

90

14. In a sound box, the combination with a stylus bar having a diaphragm engaging portion and a relatively movable stylus-holding portion, of a clamping member fulcrumed at an intermediate point in its length on one of said portions of said stylus bar and having a clamping end thereon arranged to engage the other portion of said bar, and means coöperative with the other end of the clamping member and the portion of the bar on which the clamping member is fulcrumed to exert a clamping engagement between the clamping end of said member and said other portion of said bar which it engages.

95

15. In a sound box, the combination with a stylus bar having a relatively movable stylus-holding portion adapted to occupy different playing positions, of a clamping member fulcrumed at a point intermediate its length on the movable portion of said bar, one end of said member being adapted to engage and clamp the other portion of the bar, and a screw coöperative with the opposite end of said member to exert a clamping pressure between the first mentioned end of said member and the part of the stylus bar which it engages.

110

115

120

16. In a sound box, the combination with a stylus bar having a relatively movable stylus-holding portion, of a clamping member, a screw operative as an adjustable fulcrum to connect an intermediate portion of said member to the movable portion of the stylus bar, one end of said member being adapted to clamp the other portion of the stylus bar, and an operating screw coöperative with the opposite end of said mem-

125

130

ber to exert a clamping action between the first mentioned end of the clamping member and the portion of the stylus bar which it engages.

5 17. In a sound box, the combination of a stylus bar comprising a main portion and a stylus-holding portion pivotally connected therewith; said stylus-holding portion itself consisting of a pair of parts which at said pivotal connection straddle and are adapted to clamp the main portion of the stylus bar between them, one of said pair of parts be-

ing adapted to hold the stylus and the other being a clamping member fulcrumed at an intermediate point in its length on the 15 stylus-holding part with one of its ends in the aforesaid clamping relationship; and means coöperative with its other end for forcing it away from said stylus-holding part.

20 In testimony whereof I have heretunto set my hand.

ROBERT HEAD
